UNITED STATES PATENT OFFICE.

HOWARD I. SAWYER, OF POMEROY, WASHINGTON; FRANK OLESON, ADMINISTRATOR OF SAID HOWARD I. SAWYER, DECEASED, ASSIGNOR TO H. I. S. MOTOR CORPORATION, OF POMEROY, WASHINGTON, A CORPORATION OF WASHINGTON.

EXPLOSIVE-MOTOR.

1,360,690.

Specification of Letters Patent. Patented Nov. 30, 1920.

Application filed March 20, 1920. Serial No. 367,344.

To all whom it may concern:

Be it known that I, HOWARD I. SAWYER, a citizen of the United States of America, residing at Pomeroy, in the county of 5 Garfield and State of Washington, have invented certain new and useful Improvements in Explosive-Motors, of which the following is a specification.

The primary object of the invention is the 10 provision of an explosive motor in which the piston is given an impulse stroke at each extremity of its reciprocating path of travel when such is found to be desirable, under the control however of suitable timing 15 means, the construction being simple and possessing great strength as well as being provided with efficient cooling means.

A further object of the invention is to 20 provide an explosive motor having an auxiliary charge adapted for direct ignition for firing the main charge in the explosion chamber at a predetermined time, the initial charge and main charge being automatically controlled upon the operation of 25 the piston.

A still further object of the invention is 30 to provide an explosive motor providing maximum cooling surface for the cylinders and having readily accessible charge ignition means, the reciprocations of the piston toward each end of the motor automatically feeding and igniting charge to the ignition means as well as compressing the main charge for a suitably timed explosion to 35 impart the power impulse to the piston.

With these general objects in view the invention consists of the novel combination and arrangement of parts hereinafter more fully described in connection with the accompanying drawings and in which like reference characters designate corresponding parts throughout the several views.

In the drawings,

Figure 1 is an elevational view of the invention partially broken away,

Fig. 2 is a view partly in elevation of the adjacent side thereof, mainly illustrating the invention in central longitudinal section with the piston positioned adjacent one 50 extremity of its longitudinal movement,

Fig. 3 is a central longitudinal sectional

view through a portion of the cylinder wall and piston taken upon a plane perpendicular to the plane of section of Fig. 2, with the cylinder heads removed,

55

Fig. 4 is a view similar to Fig. 2, showing considerable of the cylinder in side elevation, the piston being at substantially the opposite limit of its stroke, and Fig. 5 is an elevational view of the opposite side of the 60 invention from that illustrated in Fig. 4.

Referring more in detail to the drawings, a motor cylinder 10 is provided having a suitable water cooling space 11 with closing heads 12 at its opposite ends provided with 65 water-receiving space 13 communicating with the space 11 when the cylinder heads are in position. Each head 12 comprises a disk portion 14, and a cup-shaped portion 15, the latter projecting inwardly of the 70 bore 16, of the cylinder, when the device is assembled and having a chamber 17, normally filled with water from the cooling spaces 13 and 11. The heads 12 are secured in position in any manner desired, while a 75 circulating means for the cooling water within the spaces 11 and 13 and chamber 17 may also be provided in substantially the usual manner and unnecessary to herein illustrate.

80

A tubular piston 18 adapted to reciprocate within the cylinder bore 16, is herein illustrated preferably comprising a casting iron sleeve 19 with an aluminum covering or outer layer 20, the sleeve 19 being shrunk 85 into the said covering 20 while suitable packing rings 21 are provided encircling and countersunk in the outer surface of said covering 20, and packings 21' are provided adjacent the inner ends of the cylinder head 90 portions 15. Rods 22 are secured to the piston in any suitable manner such as by threading the ends 23 thereof into the covering 20 as best illustrated in Fig. 2 of the drawings, the said rods extending through 95 suitable passages 24 in the adjacent head 12, for operable connection with a power member such as a crank shaft not shown.

Manners of operatively connecting the piston to a driven element are set forth in 100 my Letters Patent No. 1,316,192, dated September 16, 1919, and upon which invention,

the herein described invention constitutes an improvement.

A central partition 25 in the piston 18 divides the interior thereof into two equal chambers 26 within which project the cup-shaped portions 15 of the heads 12, as shown in Fig. 2 of the drawings. A gasoline manifold 27 of any suitable form receiving explosive mixture from any suitable source 10 of supply is carried by the cylinder 10 communicating with ports 28 through the side of the cylinder terminating as at 29, adjacent the opposite ends of the bore 16, and having inwardly opening check valves 30 15 of any suitable form preventing outward movement of the explosive mixture after being drawn into the bore 16 by the movements of the piston 18.

Openings 31 are provided through the 20 side of the cylinder 10 for receiving spark plugs 32, pockets 33 being formed at the inner ends of the spark plug openings 31, for receiving an initial ignition charge through passages 34, in the wall of the cylinder leading 25 toward the opposite ends thereof, and opening as at 35, adjacent the opposite ends of the cylinder bore 16.

A diagonal opening 36 extends outwardly from each chamber 26 for alternately registering with one of the pockets 33 and exhaust port 37 in the side of the cylinder 10, an exhaust pipe 38 being provided for said opening 37 if desired.

Inlet passages 39 longitudinally of the 35 piston 18 are provided at opposite sides of the piston in sets, three inlet passages being herein illustrated in each set, terminating at corresponding ends in ports 40 adjacent the ends of the chambers 26, with the opposite ends 41 of the passages 39 terminating in the outer surface of the piston covering 20, adjacent the relatively opposite end of the piston as best illustrated in Fig. 3 of the drawings.

In operation, the movement of the piston 18 away from one end of the bore 16 draws 45 an explosive charge thereinto through the inlet port 29 from the gasoline manifold 27 while the return stroke of the piston compresses the charge in said end of the bore 16, forcing a small quantity through the passage to the pocket 33, the inner end of which pocket is at such times normally closed by the adjacent side of the piston 18. A plurality of by-pass channels 42 are provided adjacent the ends of the bore 16 in the cylinder wall for registry with the ports 41 when the piston 18 nears the extremity of its stroke in a corresponding direction 55 during the compressing of the charge in the end of the bore 16, which is being approached by said piston. When the ports 41 register with the by-pass channels 42, the explosive charge passes from the adjacent 60 end of the bore 16, through the passage 39

and into the chamber 26, in the opposite end of the piston 18, through the ports 40.

In this manner, the pocket 33 of one explosive chamber 26 receives its ignition charge while the explosion chamber 26 at 70 the corresponding end of the motor is compressing its charge between the partition 25, of the piston, and the end cap 43 of the adjacent cylinder head 12. It will be understood however, that simultaneously therewith, the explosive charge is being delivered into the opposite explosion chamber 26 through the ports 40 thereof, so that simultaneously with the reception of a charge of explosive mixture in one explosion chamber, 26, the charge is being compressed in the other explosion chamber and an initial, igniting charge is being received through the adjacent passage 34 into the pocket 33 for ignition by the adjacent plug 32 and the firing of such compressed charge through the registering opening 36, of the piston.

The charge-receiving chamber 26 is exhausting through the opening 36 thereof, registering with the exhaust outlet 37, when 90 the opposite explosion chamber 26 is under compression with the charge therein ready for ignition to impart an impulse or stroke to the piston 18 upon the firing thereof at a suitably timed instant by the ignition of the 95 small quantity of explosive mixture within the adjacent pocket 33 at the end of the motor at which the piston 18 is substantially at the end of its compression stroke.

My motor may be positioned either vertically, obliquely, or horizontally for active operation and when in the vertical position as shown in Figs. 1, 2, 4 and 5, of the drawings, it will be apparent that the upper pocket 33 having received an ignition 100 charge from the upper end of the bore 16, during the upward movement of the piston 18, will explode the compressed mixture between the cylinder head portion 43, and the partition 45, thereby causing the lowering 110 of the piston upon one of its power strokes. During the downward movement of the piston 18, the upper explosion chamber 26 is exhausted when the passage 36 of said upper explosion chamber registers with the 115 exhaust opening 37 while such downward movement of the piston operates in a similar manner for compressing and exploding the charge in the lower explosion chamber 26 on the upward power stroke of the piston. The downward stroke of the piston draws a 120 new charge of explosive mixture through the inlet passage 28 to the upper end of the bore 16, and also clears the small passage 34, such downward movement also forcing 125 a new charge of explosive mixture through the ports 40, passages 39, and ports 41 from the lower end of the bore 16, into the upper explosion chamber 26 when the piston is substantially at the lower extremity of its 130

movement, as indicated by dotted lines in Fig. 4 of the drawings.

The introduction of a new charge to the lower explosion chamber 26 is accomplished 5 in a similar manner when the piston has reached substantially its upper limit of movement as illustrated in Fig. 2 of the drawings. From this description it will be seen that the pocket 33 for one explosion 10 chamber 26, is being filled simultaneously with the compressing of the charge in its explosion chamber while the feeding of a new charge to the opposite explosion chamber is also taking place at such times.

15 An explosive impulse is imparted to the piston 18 when the piston is approximately positioned at its opposite extremities of longitudinal movement.

The complete operation of the invention 20 will be fully understood from this detailed description thereof, and while the preferable embodiment thereof is herein set forth, it will be understood that minor changes may be made therein, without departing from the spirit and scope of my invention.

What I claim as new and desire to secure by Letters Patent is:—

1. An explosive motor comprising a cylinder, a head upon one end of the cylinder projecting inwardly of the bore thereof, a spark plug in the side of the cylinder, a reciprocating piston within the cylinder having an explosive chamber therein, and with a combined inlet and exhaust passage through the piston communicating with said chamber and adapted to register with said plug when the explosive charge is under compression with the piston positioned approximately at 35 one extremity of its stroke, whereby the charge is adapted for ignition by the plug during operation, the cylinder being provided with a passage for explosive mixture leading from a point adjacent one end of the 40 bore of the cylinder to a point adjacent the sparking end of the plug whereby an initial igniting charge is furnished to the plug for igniting the explosive charge in the explosion chamber through said combined inlet and exhaust passage of the piston and means for supplying a fresh charge of explosive mixture to the explosion chamber when the piston is positioned at substantially the opposite extremity of its movement.

55 2. An internal combustion engine comprising a cylinder, heads closing the opposite ends of the cylinder, with cup-shaped portions projecting axially within the bore of the cylinder, the side wall of the cylinder having an exhaust opening and spark plug openings at the opposite sides of said exhaust opening, spark plugs in said spark plug openings, a tubular piston reciprocatingly mounted in the bore having a central

partition providing an explosion chamber in each end of the piston with the wall of the piston having angular openings communicating with said chambers adjacent the partition, and adapted to register alternately 70 with the spark plug openings selectively and with said exhaust opening, whereby an operative explosion in one chamber and the exhausting of the opposite chamber is simultaneously effected upon each stroke of the 75 piston, the piston being provided with sets of longitudinal passages terminating at the periphery of the piston adjacent the opposite ends thereof with the other ends of each set of longitudinal passages in letting adjacent the opposite ends of said explosion chambers, the inner wall of the cylinder having by-pass grooves adapted for registry with the peripheral terminating ends of said 80 passages whereby explosive mixture to one 85 of said chambers is effected from a point adjacent the opposite end of the bore at each reciprocation of the piston, the cylinder being provided with an inlet port for explosive mixture adjacent the opposite ends of 90 the bore whereby explosive mixture is adapted to be drawn into the end portions of the bore during the reciprocations of the piston inwardly away from said inlet ports selectively, the wall of the cylinder having longitudinal 95 passages leading from points adjacent the ends thereof, to pockets formed in the inner end portions of the spark plug openings inwardly of said plugs when operatively positioned, whereby the pocket for 100 the plug in one end portion of the cylinder is supplied with an initial ignition charge simultaneously with the compressing of the explosive charge in the adjacent explosion chamber and the supplying of an explosive 105 charge to the opposite explosion chamber.

3. An explosive motor comprising a cylinder having an exhaust and a spark plug opening in the side thereof, a spark plug partially projecting within said spark plug 110 opening, forming a pocket inwardly of the plug, a reciprocating piston within the cylinder having an explosion chamber therein, and a side passage leading from said chamber adapted for alternate registry with said openings, means for supplying an explosive charge to the chamber and means for supplying an initial ignition charge of explosive mixture to said pocket whereby 115 upon the operative sparking of the plug, the charge within the pocket is adapted for ignition communicating through said side passage of the piston to the main charge within said explosion chamber.

4. An explosive motor comprising a cylinder, a reciprocating piston within the cylinder having an explosion chamber within the piston, and a combined firing and exhaust passage for said chamber provided through the piston, the cylinder having a plug open- 125 130

ing and an exhaust opening adapted to alternately register with said passage when the piston is adjacent the opposite extremity of its movement, a spark plug projecting into said plug opening providing an ignition pocket inwardly of the plug, means adapted for supplying explosive mixture to said

10 pocket and explosion chamber during successive reciprocations of the piston and igniting means for the mixture in said pocket adapted for operation when said passage is in substantial registry with said pocket.

In testimony whereof I affix my signature.

HOWARD I. SAWYER.
